HAROLD A. DODGE, OF NEWARK, NEW JERSEY.

PACKAGING TOY BALLOONS.

1,168,381.

Specification of Letters Patent. Patented Jan. 18, 1916.

Application filed July 11, 1914. Serial No. 850,311.

To all whom it may concern:

Be it known that I, HAROLD A. DODGE, a citizen of the United States, and a resident of Newark, in the county of Essex and State of New Jersey, have invented certain Improvements in Packaging Toy Balloons, of which the following is a specification.

The objects of this invention are to package a toy balloon with its stick so as to enable the same to be handled as a unit and thus facilitate distribution and sale of them; to prevent crumpling and damaging the balloon, and to utilize the rigidity of the stick for that purpose; to prevent the balloon from shifting unduly in said package; to enable the balloon to be delivered in good sanitary condition for applying to the lips to expand it; to position the balloon within the package so that a plurality of such packages may be compactly stored; to secure simplicity and cheapness, and to obtain other advantages and results as may be brought out in the following description.

Referring to the accompanying drawings, in which like numerals of reference indicate the same parts throughout the several views, Figure 1 is a perspective view of a sealed package containing a toy balloon and stick ready for delivery according to my invention; Fig. 2 is a similar perspective view with parts of the envelop torn open; Fig. 3 is a transverse sectional view on line A—A of Fig. 1, and Fig. 4 is a longitudinal edge view of a closed package containing a toy balloon and its stick.

In the specific embodiment of the invention illustrated in said drawings, the reference numeral 1 indicates a deflated toy balloon adapted to be inflated by the purchaser through its open end or mouth-piece 2. Such balloons are usually made from a thin elastic material which allows the balloon to increase to a considerable size by filling with air and is subject to considerable strain when so filled, and any weakness of the material results in rupture and ruin of the balloon. It has been found in the sale of these toys that to handle the balloons and sticks loosely mixed not only results in confusion and great loss of time, but also the delicate material of the balloons is crumpled and creased and damaged either before or after delivery to purchasers, so that the balloons often spring a leak when inflated. Although not actually punctured, the bal-

loon is likely to have weak places which enlarge and stretch when the balloon is inflated, until the material ultimately tears. Both the mouth piece and the sticks are liable to injure the balloons or actually 60 punch holes in them when the balloons and sticks are promiscuously mixed and handled together. Also, merely to crease the balloon material one way, for instance in a longitudinal direction or direction axially of 65 the mouth-piece, and then crease it again transversely thereto, results in a weak spot at the intersection of the two creases which under the strain of inflation will break through, and it is desirable to keep the balloons out smooth so that they cannot get creased that way.

According to my invention, I lay the deflated balloon 1 longitudinally of the stick 3 which is sold with it for a handle, near 75 one end thereof, so that the stick will prevent transverse creasing of the balloon; in this position and relation I place them within an envelop 4 long enough to receive the stick but not wide enough to allow the balloon to shift with respect to the stick, as shown. Preferably I make the envelop 4 of such size that the balloon will frictionally engage the walls thereof and remain in substantially the position stated regardless 80 of the usual and ordinary handling of the package. In this manner, the only creasing of the balloon occurs in a longitudinal direction necessary to reduce the spherical shape 85 of the balloon to a flattened shape, and the mouthpiece 2 is prevented from doing any harm; also the stick 3 is held with its ends covered and is prevented from injuring the balloons, and furthermore the stick is utilized to keep the collapsed balloon in shape 90 and aid in its safe handling and transportation. Obviously, in packaging the balloons this way, the thickness of the balloon will make a bulge 5 in the package, and in order 95 that the packages may be stored as compactly as possible, I preferably position the balloon at one end of the package as close to the end of the stick as practicable without endangering the balloon to damage by the stick, so that in stacking the packages one 100 may be laid with the bulge at one end of a pile and the next with the bulge at the other end, making a compact and neat arrangement. Inasmuch as the balloon will not slide 105 in the package normally, its disposition 110

which I have described therefore enables and facilitates the convenient stacking or piling up of the packages.

In order to deliver the balloons to the purchaser in sanitary condition and free from infective germs, I preferably seal the package by means of opposite end flaps 6, 6. This insures that when the child inflates the balloon, the mouth-piece 2 is clean for him to take between his lips.

Having thus described the invention, what I claim is:

1. The combination of a collapsed balloon and a stick therefor several times as long as the same, said balloon and stick being separate and detached from each other and arranged longitudinally side by side, and an envelop inclosing said stick and balloon otherwise separate and detached from them except for a frictional engagement with the balloon which will hold it in such position that the stick prevents bending and crumpling of the balloon.
2. The combination of a collapsed balloon and a stick therefor several times as long as the same, said balloon and stick being separate and detached from each other and arranged longitudinally side by side with

the balloon near one end of the stick, and an envelop inclosing said stick and balloon otherwise separate and detached from them except for a frictional engagement with the balloon which will hold it against both lateral and longitudinal displacement with respect to the stick, whereby the stick prevents bending and crumpling of the balloon and two similar such packages will lie compactly together with the bulge of one against the opposite end portion of the other.

3. The combination of a collapsed balloon and a stick therefor several times as long as the same, said balloon and stick being separate and detached from each other and arranged longitudinally side by side, and a rectangular envelop inclosing said stick and balloon with its length corresponding to the length of the stick and its width such that the envelop receives the balloon with sufficient friction to prevent displacement of it longitudinally, said envelop being otherwise separate and detached from the stick and balloon.

HAROLD A. DODGE.
